UNITED STATES PATENT OFFICE.

ERNEST W. GAUBE, OF CLEVELAND, OHIO.

SPRAYING DEVICE.

1,114,252.

Specification of Letters Patent.

Patented Oct. 20, 1914.

Application filed July 3, 1913. Serial No. 777,178.

To all whom it may concern:

Be it known that I, ERNEST W. GAUBE, a citizen of the United States, residing at Cleveland, in the county of Cuyahoga and State of Ohio, have invented a new and useful Improvement in Spraying Devices, of which the following is a specification, the principle of the invention being herein explained and the best mode in which I have 5 contemplated applying that principle, so as to distinguish it from other inventions.

My invention has general reference, to a spraying device and is associated more particularly with a construction of the character 10 stated adapted for the disintegration of rather viscid fluids.

The objects of the invention are: First, to provide a device which while sufficiently small for pocket transportation will nevertheless 15 prove efficient. Second, the accomplishment of a movable relationship between two parts whereby a closure is affected. Third, an arrangement such that the whole is more compact when closed, to 20 permit of its being accommodated in a receptacle having the minimum dimensions. Fourth, the provision of a device of comparative simplicity and hence economically 25 feasible of manufacture.

30 The inventive conception is embodied in means which are hereinafter explained and variously combined in the claims, while the annexed drawing and particular description thereof, together set forth in detail one 35 certain means constituting my invention, the disclosed means however, being but one of various mechanical forms in which the principle of my invention may be applied.

Figure I is a vertical section of a spraying device embodying my invention, one 40 part being indicated by dotted lines in an altered position to fit the box also shown. Fig. II is a section on line II II of Fig. I looking downwardly as suggested by the arrows. Fig. III is a section on line III III 45 of Fig. I looking upwardly.

A container A which is usually though not necessarily glass is seen in the drawing. This is intended to contain the medicinal 50 substance which it is desired to have diffused by my inventive device. This container is screw-threaded at a' around its upper opening.

I provide a tubular cap member B fash- 55 ioned with complementary interior screw-

threads b' through the agency of which it may be firmly seated upon or removed from the container. This cap member B is moreover fashioned with five openings each intersecting its upper surface, four also its under surface, while a fifth extends obliquely therethrough to emerge at one side. The largest of these five openings, I have designated as b^2 and this is in fact a central opening. Another opening b^3 extending directly through the top of the cap is disposed somewhat to one side as clearly seen in Figs. II and III. This opening has only its lower half screw-threaded for the selected purpose to be presently described. 60 Two other openings each designated as b^5 likewise extend through the cap member B and are situated on opposite sides respectively of the openings b^2 and b^3 . The fifth opening b^6 is smaller and rather more precisely and oblique duct intersecting or communicating with the upper portion of the opening b^3 slightly below the upper surface of the cap as clearly seen in Fig. I. Continuing downwardly and laterally this duct 65 b^6 is enlarged where it emerges at the side and this enlarged portion is screw-threaded at b^7 . 70

A hollow member C having a lower portion c' with a mainly flat under surface 75 adapted to present a ground surface contact with the smooth upper surface of the cap member B, also has a central cylindrical projection c^2 of such length that it may project through the opening b^2 a sufficient distance beyond the under side of the cap B. The cap opening b^2 and the projection c^2 should present a close pivotal fit relative to 80 each other in order that the member C can be rotated upon the cap B. A spring 85 washer c^3 surrounds the lower extremity of the projection c^2 and is held in yielding contact with the under surface of the cap B through the medium of a bent pin c^4 extending through a suitable opening in the lower 90 end of the projection. In this manner the movable connection between the hollow member C and cap B may be held in any predetermined position of rest. The hollow member C is provided above and on one 95 side with an opening c^5 communicating with the interior thereof. The opposite side of the member C is formed as an upwardly inclined spout c^6 having an opening c^7 . It is 100 this construction that constitutes the nozzle. 105

zle proper. The lower portion c' is provided on that side of its center which is directly underneath the opening c^5 or on that side which is opposite to that from which the spout c^6 projects, with a blunted crescent-shaped opening c^8 . This opening is clearly represented in Fig. II, and its size is such that it will simultaneously expose or register with the opening b^3 and both openings b^5 .

A siphon tube E is screw-threaded a slight distance from its upper end at e' and is adapted to be fitted into the screw-threads b^4 . As so positioned, the tube E which is open below depends to within a short distance of the bottom of the bottle A. Its upper extremity is tapered at e^2 as clearly seen in Fig. I, while the end surface is preferably flush with the under surface of the portion c' . It is this tapered surface therefore that is interposed across the upper opening or outlet of the duct b^5 .

A knob F has a small screw-threaded portion f' engaging with the screw-threads b^7 . This knob is provided with a central duct f^2 to register with the lower end of the duct b^6 as is well shown in Fig. I. One end of a hose f^3 is secured to the knob F and suspended from the opposite end of the former is a bulb f^4 adapted to force a blast of air up through the duct b^6 .

As is illustrated in Fig. I an inclosing box G is of such size that it will wholly inclose my spraying device only when the nozzle proper c^6 has been rotated so as to be disposed over the knob F. I have purposely contrived the disposition of the openings in both the cap B and the hollow member C in a manner such that those leading through the cap B to the supply of fluid are closed and the device as a whole therefore prevented from leaking when it is not desired to use it. In order therefore to pack the device in the box G one is manifestly compelled to rotate the spout c^6 into its closed portion.

The operation of my spraying device is as follows:—it being presumed that the nozzle proper c^6 has been disposed in substantially the same vertical plane as the knob F. In this position the extensive opening c^8 is disposed nearest that side of the cap member B which is opposite to the side having the opening b^3 and the two openings b^5 . Consequently while in such position the surface c' overlies and hence closes all three of these openings and necessarily the discharge end of the duct b^6 as well. It is furthermore obvious that in order to project a blast through the duct b^6 and thereafter through the spout c^6 , it is required to first rotate the hollow member C through an angle of approximately 180 degrees or until the opening c^8 uncovers or registers both with the opening b^3 and at least one of the openings b^5 . The opening c^5 is pro-

vided to supply additional venting in case this should become necessary. As should now be apparent any sudden compression of the bulb f^4 serves to expel a blast of air through the duct b^6 against the tapered surface of the siphon tube E. A sufficient vacuum is thereby established in this latter to draw the fluid up into the tapered portion thereof. Such fluid is then disintegrated in the usual manner into small particles and disseminated so that the same may be emitted from the spout in the form of a fine spray.

My construction requires a comparatively small bulb for the successful distribution of the rather oily medicinal fluid which it may be desired to have injected into the throat or nostrils for treatment say, of hay fever. The tapered formation imparted to the upper extremity of the siphon tube E is responsible for the measure of increased efficiency inasmuch as it tends to more effectively disrupt the cohesiveness of fluids having the properties stated.

The substantial alinement of the upper discharge end of the blast duct b^6 with the spout c^6 when the latter is in its open position, also contributes toward the attainment of a more thorough disintegration by occasioning a direct route of blast travel into which the tapered portion projects.

My invention being thus described with sufficient thoroughness, what I desire to secure by Letters Patent and therefore claim specifically, is:

1. As a new article of manufacture, a spraying device of the character described comprising the combination of a member having an opening, a hollow member extending therethrough and having its one extremity flush with one side of said first mentioned member, said hollow member being furthermore provided adjacent such extremity with a surface sloping away from said first mentioned member, a blast duct having a discharge opening opposed to said surface, and a nozzle movably attached against said side and having a duct adapted to communicate with said hollow member, such communication being closed by the movement of said nozzle.

2. As a new article of manufacture, a spraying device of the character described comprising the combination of a member formed with siphon and blast ducts converging to a common outlet, and a nozzle movably carried by said member and having a duct in communication with said first mentioned ducts, the relative movement of said member and nozzle being adapted to close such communication.

3. As a new article of manufacture, a spraying nozzle of the character described comprising the combination of a siphon tube having its outlet end tapered and a blast

duct having an outlet intersecting the surface of said tapered portion, said blast duct being inclined relative to the inclination of said tapered portion, and means for successively closing said outlets.

4. As a new article of manufacture, a spraying nozzle of the character described comprising the combination of a container, a cap therefor provided with an opening, a siphon tube projecting through said opening, said tube being tapered at its upper end, said cap itself formed with a duct intersecting said cap opening, a nozzle movably secured to said cap, said nozzle having an outlet in communication with said cap opening and means carried by said nozzle and adapted to close said cap opening.

5. As a new article of manufacture, a spraying nozzle of the character described comprising the combination of a cap having an opening, a duct extending obliquely through said cap and intersecting said opening, a nozzle movable relatively to said cap and provided with an opening adapted to register with said cap opening and means for simultaneously closing said openings.

6. As a new article of manufacture, a spraying nozzle of the character described comprising the combination of a cap formed with a pair of ducts converging upwardly to a common outlet, a nozzle rotatably mounted upon said cap and itself provided with a pair of openings adapted to register with said outlet, the arrangement being such that said outlet may be closed by the relative movement of said cap and nozzle.

7. As a new article of manufacture, a spraying device of the character described comprising the combination of a member formed with a pair of ducts converging to a common outlet, means for creating a blast in one such duct, and a member movably carried by said first mentioned member and provided with a duct in a direct line of communication with said blast duct, the relative movement of said members being adapted to close said ducts.

8. As a new article of manufacture, a spraying device of the character described comprising the combination of a cap formed with a pair of openings, a siphon tube extending through one of said openings and flush with one side of said cap, said cap furthermore fashioned with a duct converging toward said tube opening, and a nozzle having a plurality of openings and rotatable upon said cap, one of said nozzle openings

being adapted to simultaneously register with said cap openings.

9. As a new article of manufacture, a spraying device of the character described comprising the combination of a cap having an opening, said cap also formed with a blast duct extending obliquely toward and intersecting said opening, and a member carried by said cap and movable relatively thereto, said member having a nozzle opening in communication with said first opening, such communication adapted to be controlled by said relative movement. 70

10. As a new article of manufacture, a spraying device of the character described comprising the combination with a member formed with siphon and blast ducts converging to a common outlet, said blast ducts having a lateral receiving opening, blast creating means operatively connected with said opening, a member rotatably carried by said first mentioned member and having a laterally projecting nozzle adapted to communicate with said ducts, the arrangement being such that said nozzle may be closed by its rotation into the plane of said opening, for the useful purpose specified. 75

11. As a new article of manufacture, a spraying device of the character described comprising the combination of a siphon duct, a member provided with a blast duct, the openings of said ducts being angularly opposed, and a nozzle rotatably carried by said member and projecting laterally beyond the same, said nozzle adapted to communicate with said duct openings, the arrangement being such that said communication may be closed by the rotation of said nozzle. 80 90 95

12. As a new article of manufacture, a spraying device of the character described comprising the combination of a member provided with a siphon and a blast duct converging toward a common outlet, blast creating means connected with said blast duct and disposed laterally of said member, and a nozzle rotatably mounted upon said member and communicating with said common outlet, said nozzle projecting laterally beyond the opposite side of said member, the rotation of said nozzle being adapted to close communication therethrough. 100 105

Signed by me, this 30th day of June, 1913.

ERNEST W. GAUBE.
